(57) **CLAIM**

The ornamental design for a wheel rim, as shown and described.

DESCRIPTION

FIG. 1 is a front perspective view of a wheel rim according to my invention

FIG. 2 is a front view thereof;

FIG. 3 is a rear view thereof; and,

FIG. 4 is a rear perspective view thereof.

The broken lines showing of the rear of the wheel rim is included for the purpose of illustrating environment and forms no part of the claimed design.
